ALEXANDER KELLEY, OF WILMINGTON, DELAWARE, ASSIGNOR TO CLIMAX MACHINE CO., OF WILMINGTON, DELAWARE, A CORPORATION OF DELAWARE.

DELIVERY MECHANISM FOR MATCH-MACHINES.

1,266,953.

Specification of Letters Patent. Patented May 21, 1918.

Application filed July 24, 1917. Serial No. 182,593.

To all whom it may concern:

Be it known that I, ALEXANDER KELLEY, a citizen of the United States, residing at Wilmington, in the county of New Castle and 5 State of Delaware, have invented certain new and useful Improvements in Delivery Mechanisms for Match-Machines, of which the following is a specification.

This invention relates to match machines 10 and has special reference to the delivery mechanism whereby the finished matches are withdrawn from the conveyer and delivered to the packaging machinery or conveyed to points where they may be otherwise 15 handled and prepared for the market. The object of the present invention is to provide means whereby the matches will be positively released from the conveyer and withdrawn therefrom and simultaneously 20 deposited upon the delivery belt. The invention also seeks to provide means whereby any stumps of matches which may be broken in the conveyer will be expeditiously withdrawn so that when the conveyer is again 25 presented to the splint-making mechanism, the members of the conveyer will be free of all obstructions and in proper condition to receive and hold the splints.

The invention is illustrated in the accompanying drawings, in which:

Figure 1 is a side elevation of the delivery mechanism of a match-making apparatus;

Fig. 2 is an enlarged longitudinal section of the same;

Fig. 3 is a plan view thereof;

Fig. 4 is an end elevation;

Fig. 5 is a perspective view of the jaw opening device;

Fig. 6 is a perspective view of the device 40 for withdrawing stumps of broken matches;

Fig. 7 is a detail transverse section of the same.

The supporting frame 1 may be of any preferred type. The matches are carried 45 from the splint-forming mechanism, past the dipping tanks and over a tortuous path by a conveyer 2 which is of such length that when the matches reach the delivery mechanism their heads will be thoroughly dried 50 and the matches in proper condition to be used, as will be readily understood by those skilled in the art. The conveyer employed by me consists essentially of resilient jaws 3 adapted to be automatically opened by 55 the forcing of splints thereinto and firmly gripping the matches by virtue of their own

resiliency. The construction herein disclosed is fully described in Letters-Patent No. 1,168,810 granted to me Jan. 18, 1916. At the delivery end of the apparatus the conveyer is carried around a drum or sprocket wheel 4 and the tracks by which the conveyer is guided are so disposed relative to the drum or sprocket wheel 4 that, as the rows of matches approach and pass the delivery point, they will be on radii of the drum and, consequently, will be spread slightly apart at their outer free ends. A delivery belt 5 is arranged adjacent the drum 4 and is mounted upon suitable rollers 6 carried in a frame 7 secured to and projecting from the main frame 1. One of the rollers 6 has its shaft 8 extended beyond the side of the frame 7 and is there equipped with a large pulley 9 having an overhanging rim 70 upon which may be formed an internal gear. Between the bight of the delivery belt or apron 5 and the delivery drum 4, a corrugated feed roller 10 is provided, said roller having its shaft journaled in suitable bearings on the frame 7 and having the said shaft extended at one end and equipped with a pulley or pinion 11 adapted to engage the overhanging rim or internal gear of the pulley 9. The corrugated roller will, consequently, be rotated in the same direction as the delivery apron and it should be so arranged that its periphery will extend up into the same horizontal plane as the upper run of the said apron or belt. By reference 80 to Fig. 2, it will be noted that as the conveyer moves downwardly the matches, indicated at 12, will be brought against the constantly rotated corrugated feed roller 10 and will be engaged by said roller with sufficient force to be positively withdrawn from the jaws 3. In order that the jaws may be 85 positively opened to release the matches, I provide an opener consisting of a reciprocating block 13 provided with fingers 14 at its inner edge, the said block being movable toward and from the conveyer jaws 3 so that the fingers 14 will be forced in between the jaws and then withdrawn during the interval that a row of matches is in contact with the roller 10. The block 13 is provided with 90 ribs or cleats 15 at its ends which engage guides 16 on the sides of the frame 7 whereby the block will be caused to move in a direct line and will not be carried out of the 95 position in which the fingers 14 may enter the conveyer jaws. The block is further

provided with pins or trunnions 17 at its ends which enter slots 18 in the upper ends of the pitmen 19 rising from a rock shaft 20 which is journaled in suitable bearings upon the frame 7. At the ends of the rock shaft 20 are cranks 21 having pins 22 at their ends engaging the grooves 23 of the cams 24 which are secured rigidly to the ends of a shaft 25 journaled in suitable bearings upon the main frame. This shaft 25 is equipped at one end with a pulley 26 and a belt 27 is trained around the said sprocket and also around the pulley 9 on the shaft 8 so that the rotation of the shaft 25 will be transmitted to the upper shaft 8, as will be readily understood.

At the center of the shaft 25, I secure thereto a beveled gear 29 meshing with a similar gear 30 on the upper end of a shaft 31 which is mounted in suitable bearings upon the main frame and extends downwardly so as to be connected through gearing, shown at 32, to the main driving shaft 33 extending longitudinally of the apparatus.

As it sometimes happens that matches are broken off and stumps left in the conveyer jaws 3, I provide means for withdrawing said stumps so that when the conveyer is again presented to the splint forming mechanism it will be free of obstructions which would interfere with the proper insertion of the splints in the conveyer. This stump withdrawing mechanism comprises a transversely disposed suction cup 34 carried by and between the upper ends of pitmen 35 which are mounted upon the main frame and are equipped at their lower ends with pins 36 engaging cams 37 on a transverse shaft 38 which is equipped with a gear forming a part of the train indicated at 32. The pitmen 35 will thus be reciprocated vertically so that fingers 39 provided on the upper open side of the suction cup 34 will be projected between the conveyer jaws 3 and will spread said jaws so as to loosen any stumps that may possibly be retained therein. The suction cup 34 is connected through a hose or other conduit 40 with suction pump 41 so that a strong suction is constantly acting through the said cup.

As shown most clearly in Figs. 6 and 7, the opener fingers 39 are formed on the upper edges of blocks 42 which are disposed transversely of the suction cup and within the same. These blocks are provided with stems 43 projecting through the side of the cup and a bar 44 connecting the upper ends of the pitmen 35, set screws 45 being mounted in said bar to secure the stems therein. The blocks are spaced from the bottom of the cup to provide free passage for the stumps and the suction tube 40 is preferably connected to the cup at one end there-

of with the bottom of the cup inclined toward that end to facilitate the flow to and into the tube.

It is thought the operation will be readily understood from the foregoing description, taken in connection with the accompanying drawings. The cams 37 of the shaft 38 reciprocate the pitmen 35 so that as successive rows of conveyer jaws 3 are brought over the suction cup 34 with the fingers 39 thereon, the fingers will be projected into the jaws and the jaws, consequently, spread apart. The releasing block 13 is reciprocated through the described mechanism so that it will be properly timed to force the opener fingers 14 into engagement with the conveyer jaws 3 as each successive row of jaws is brought to the delivery point. As the block 13 reaches a point adjacent the conveyer jaws 3, it will assume a position directly over the roller 10 and resist the pressure exerted by said roller upon the matches and cause the same to be effectually engaged by said roller and positively withdrawn and deposited upon the delivery apron or belt 5 which will carry them to the packaging mechanism or otherwise dispose of them, as may be desired.

My improved delivery mechanism is exceedingly simple in the construction and arrangement of its parts and will operate in a highly efficient manner to withdraw the matches from the conveyer.

Having thus described the invention, what is claimed as new is:

1. In a match machine, the combination with a match conveyer, of a constantly operating withdrawing roller disposed adjacent the conveyer and in the path of the matches therein, and a co-operating member movable to and from the conveyer across the roller to release the matches from the conveyer and press them against the withdrawing roller.

2. In a match machine, the combination with a match conveyer, of a constantly operating withdrawing roller disposed adjacent the conveyer and in the path of the matches therein, an opener movable into engagement with the conveyer to release the matches therefrom, and a carrier for said opener movable across said withdrawing member to hold the matches against the same whereby to positively withdraw the matches from the conveyer.

3. In a match machine, the combination of a match conveyer, a delivery apron disposed adjacent and extending laterally from said conveyer, a constantly operating withdrawing member disposed between the conveyer and the delivery apron in the path of matches in the conveyer, and a co-operating member movable above the delivery apron and across said withdrawing member to press the matches against said member.

whereby they will be withdrawn from the conveyer and deposited on the apron.

4. In a match machine, the combination of a match conveyer, a block movable toward and from the conveyer, fingers projecting from said block to enter the conveyer and release the matches therefrom, and a gripping roller disposed adjacent the conveyer to clamp the matches against said block.
5. In a match machine, the combination with a match conveyer, of a suction cup disposed adjacent the conveyer, opener fingers projecting from said cup, means for creating a suction through said cup, and means for moving said cup to and from the conveyer.

6. In a match machine, the combination with a match conveyer, of a suction cup disposed adjacent the conveyer, blocks disposed transversely in said cup and having stems projecting through a side of the cup, a bar through which said stems project, means for securing said stems in the bar, fingers on the

blocks projecting above the cup, means for creating suction through the cup, and means 25 for moving the cup to and from the conveyer.

7. In a match machine, the combination with a match conveyer, of a constantly rotating roller disposed across the path of the 30 matches in the conveyer, and a gripper movable toward and from the conveyer to grip the matches against said roller and positively withdraw them from the conveyer.

8. In a match machine, the combination with a match conveyer, of a withdrawing member disposed across the path of matches in the conveyer, and a gripping member movable toward and from the conveyer over said withdrawing member and adapted to 40 clamp the matches against said member whereby the matches will be positively withdrawn from the conveyer.

In testimony whereof I affix my signature.

ALEXANDER KELLEY. [L. S.]
